(57) CLAIM

I claim the ornamental design for the ring, as shown and described.

DESCRIPTION

FIG. 1 is a front perspective view of the new ornamental ring of the present invention.

FIG. 2 is a front view thereof.

FIG. 3 is a right side view, of which the left side is a mirror image, thereof.

FIG. 4 is a back view thereof; and,

FIG. 5 is a top view, of which bottom is a mirror image, thereof.
